UNITED STATES PATENT OFFICE.

MAHLON O. KASSON, OF CHICAGO, ILLINOIS.

CARPET-STRIP ANCHORAGE.

Application filed October 30, 1922. Serial No. 597,700.

To all whom it may concern:

Be it known that I, MAHLON O. KASSON, a citizen of the United States, residing at Chicago, in the county of Cook and State of Illinois, have invented certain new and useful Improvements in a Carpet-Strip Anchorage, of which the following is a specification.

This invention relates to certain improvements in a means for securing to hardened

10 floors a strip to which the edge of a carpet may be attached. The anchorage of my invention may take a variety of forms, and be used with floor, wall, and partition constructions of various kinds. The several modifications shown in the accompanying drawings are suggestive of different conditions with which the present anchorage may be employed to advantage.

20 It is a primary object of my invention to provide for the purpose named an anchorage which will be secure at all times; which may be produced and installed at small expense; and which is adaptable as well to a 25 variety of conditions in building construction. These and other objects of my invention will appear hereinafter from the specification and claims to follow, taken in connection with the accompanying drawings 30 wherein various forms of the present anchorage are set forth in the manner following:

Figure 1 which represents in cross section the lower portion of a wall or partition extending upwardly from a hardened floor, such as would result from the use of concrete, shows a carpet strip anchored in place with the aid of a device which embodies this invention;

40 Fig. 2 is a view in perspective of the anchorage per se;

Fig. 3 is a view similar to Fig. 1, showing an anchorage modified for use adjacent a wall or partition of different construction;

45 Fig. 4 is a view in perspective of the anchorage per se, which is shown in Fig. 3;

Fig. 5, which is a view similar to Fig. 1, shows a further modification of the anchorage;

50 Fig. 6 is a top plan view of the anchorage per se that is shown in Fig. 5;

Fig. 7 represents in plan an anchorage which exhibits a still further modification;

55 Fig. 8, which is a view similar to Fig. 5, shows another form of the anchorage;

Fig. 9, which is also a view generally sim-

ilar to Fig. 5, shows a form of anchorage intended for one strip only when placed adjacent a hollow wall or partition:

Fig. 10 exhibits an anchorage adapted for use with a slightly modified wall or partition construction; and

Fig. 11 represents a still further modification of anchorage adapted especially for use adjacent an outside wall of brick or masonry.

The anchorage of this invention is adapted for use with building having a construction such, for example, as is shown in Fig. 1, wherein is shown a concrete floor A from which rises a wall or partition B which may be formed hollow, or otherwise, in accordance with usual practice. Near the floor line grounds C are carried by the wall or partition as is also a plaster coating D in flush relation therewith. A base board E is also connected with the grounds in the usual manner, and adjacent thereto is a carpet strip F of approved design having its rear edge disposed beneath the base board. A tongue and groove connection between the base board and carpet strip is also shown in certain figures of the drawings, in accordance with common practice, but so far as this invention is concerned, such a formation may be wholly dispensed with, since experience has proven that it may not be safely relied upon to hold the carpet strip in place.

With a type of building construction such as has been described, the anchorage of my invention may be employed to special advantage. As shown in Fig. 2, it may consist of a plate 10 having tongues 11 struck up from its body at points which are equidistant from its ends and spaced apart from each other about the thickness of the partition tile; in addition, each plate end is formed with a plurality of pointed teeth 12 which upstand for a desired distance. As shown, these end wings are three in number, and may be offset so that the middle wing is misaligned with respect to the others. This is a preferred construction, although not essential to my invention.

An anchorage plate of the kind described is adapted to lie upon the floor and extend through or below the wall or partition which may rise from the floor in the manner shown, or otherwise. By spacing the two tongues 11 so as to lie adjacent opposite sides of the tile, the anchorage will be so centered as

to project its opposite ends for an equal distance on each side of the wall. After erecting the wall or partition, a carpet strip may be arranged on each of its opposite sides being driven to position over the pointed teeth at the plate end, by which action the teeth become embedded in the strip. By offsetting these wings in the manner shown, I practically eliminate all possibility 10 of the wood cracking or splitting during this operation. This strip in these circumstances is held securely in place upon the floor and may not be pulled away from the partition even when subjected to the very severe strain 15 imposed by a carpet which is secured thereto in the usual manner. The addition of the base board E as is customary, is primarily to present a finished appearance, but need not in any measure contribute to the present 20 anchorage except in so far as it may act to prevent its working upward and thence off of the teeth which grip therewith.

In Fig. 3 I have shown a slightly modified anchorage construction which is especially 25 adapted for use adjacent an outside wall B, such, for instance, as is formed of brick. With such a wall is associated the usual grounds C, plaster coating D, base board E, and carpet strip F, all as previously explained. An anchorage for this latter part, however, may conveniently comprise a plate 30 15 having upturned teeth 16 at one end thereof, the opposite plate end being downwardly turned as at 17 to provide in effect a 35 flange. In the plate body, it may be preferred to form one or more holes 18 and likewise other holes 19 in the flange portion thereof. An anchorage answering to this 40 description is designed for installation previous to hardening of the floor so that its flange may be embedded therein in proximity to the wall. In such a construction the concrete or mortar is free to enter the holes 18 and 19, thus adding to the security 45 of the anchorage. Because each plate is located close to the wall, it follows that its teeth are correctly positioned relative to the strip which is thereafter hammered down thereupon in the manner already explained. 50 A construction such as this, provides a secure anchorage for the strip such that it will not be displaced through pull of the carpet when attached thereto.

The anchorage forms described up to this 55 point may be modified in certain particulars without sacrifice of the features underlying this invention. In Figs. 5 to 11, inclusive, are set forth certain forms which the anchorage may take, these being offered as typical 60 of various changes in form, shape, and contour which may advantageously be employed according to the conditions created by the building construction with which the anchorage must co-operate.

65 The anchorage shown in Fig. 5 is adapted

for use with a wall construction similar in all respects to that shown in Fig. 1, and accordingly the parts which are common to the two figures bear like reference numerals. The anchorage per se consists of a plate 20 70 adapted to be rested on the floor with its ends extending laterally to each side of the wall or partition. At each plate end is an extension tongue 21 which initially protrudes beyond the forward edges of each 75 carpet strip. Upstanding teeth 22 are provided at each end of the plate body in position to enter the carpet strip when the same is driven down thereupon, as shown in Fig. 5. The plate may take the form which is 80 shown in Fig. 6 with its tongue 21 extended from a middle position at each plate end, in which event the teeth lie to either side thereof. With such an anchorage the extremities 23 of each tongue may be bent 85 upwardly and around so as to be clinched down upon the carpet strip in the manner shown in Fig. 5. Such a construction serves to reinforce the connection between the carpet strip and the anchorage which is provided therefor. 90

In Fig. 7 I have shown in plan an anchorage having many characteristics similar to that just described in connection with Fig. 6. In this construction use is made of a plate 25 whose extremities 26 are adapted to extend out beyond the forward edges of the two carpet strips. Thereafter these extremities are bent up and around so as to be clinched down upon each strip in the 95 manner described in connection with Fig. 5. Such an anchorage depends solely upon its clinched connection with the two strips to hold the same in place, inasmuch as I have not provided any teeth for gripping the strips. It should be borne in mind, however, that the teeth may be added to this construction, in which event an anchorage 100 very similar to Fig. 6 would result. Likewise if the tongues of Fig. 6 be omitted, the 105 result will be an anchorage very similar to that of Fig. 2. The tongues 11 shown in this latter figure which serve to center the plate relative to the partition, may or may not be used, according as is desired, the construction of Fig. 6 suggesting a construction where such tongues are wholly dispensed with. 115

Referring now to Fig. 8, the building construction therein shown is in all respects 120 similar to that indicated in Figs. 1 and 5, excepting that the wall or partition is indicated as hollow so as to present inner wall surfaces 27. The anchorage used in such a wall may follow identically that which is 125 shown in Fig. 2 with the one exception that the tongues 11 are shown as spaced closer together so as to lie adjacent the inner surfaces of the partition rather than the outer surfaces thereof. This difference, while 130

trifling, is nevertheless suggested at this point, as indicating one further modification which, in some cases, may be preferred. In this same figure the several teeth 12 are shown as struck up in the same plane, instead of being offset. It is not considered that this is to be preferred, but is represented as indicative of a possible modification, although very slight, from the exact form shown in Fig. 2.

Fig. 9 sets forth a wall or partition construction in all respects similar to that of Fig. 8, it being particularly noted that the partition used is hollow. The anchorage in this case is intended for holding a carpet strip on only one side of the wall or partition. This being the case the plate 36 therein shown is formed with struck-up teeth 31 at one end in position for embedment in the carpet strip, and at its other end is provided with an up-turned flange adapted to rest against one of the inner faces of the wall or partition. In this construction, as elsewhere, the carpet strip backs up to the base board, so that it may not be further moved toward the wall or partition, while the anchorage which bears against the proximate inner face of the partition serves to hold the strip against outward movement therefrom.

It may be desired to utilize my invention with wall or partition constructions wherein a combination base board and border is used. As an example of this I have represented in Fig. 10 a wall or partition B rested upon a floor 36 of concrete, a base board 37 being arranged at the juncture of the wall or partition with the floor line. This base board combines in its construction a border section 38 which is suitably supported upon a base of mortar or cement. With such a construction it is common to mold the floor with a groove which is thereafter filled by grout or mortar 40, as shown.

A wall and floor construction answering to the preceding description imposes special difficulties in the way of an anchorage for a carpet strip F such as is shown in juxtaposition to the border section 38. To anchor such a strip in position I employ a plate 41 one portion of which is rested on the floor beneath the border section 38. The end 42 of this plate portion is suitably formed for embedment in the mortar, a flange being suggested for this purpose. The other end of the plate is provided with appropriate teeth which are adapted to be driven into the carpet strip when the latter is pounded thereupon. As shown, one of these teeth 43 may be elongated to project clear through the carpet strip, permitting its extremity to be downturned or clinched thereupon. With such a construction the carpet strip is most securely held in place. I would have it noted that this provision of

an elongated tooth whose extremity projects through the upper side of the strip, thereby adapting it to be clinched thereupon, may be employed with equal advantage with any of the other constructions herein disclosed.

70

Another type of building construction where special difficulties are interposed in the way of an anchorage for the carpet strip is suggested in Fig. 11. In this case, I have represented a wall or partition B which may be made of brick or concrete. The floor in this construction is shown as monolithic, its ends being partly received and supported within the wall, as shown. The carpet strip in this case is anchored with the aid of a plate 45 having upturned teeth 46 adapted for embedment therein when the strip is driven down thereupon. As shown, the plate is provided with an upwardly extending tongue 47, struck from its body, and adapted to bear against the proximate face of the wall or partition, thereby centering the anchorage in relation to the strip which is to be held. This plate which is rested upon the floor may be provided with a crimped or corrugated rear end portion 48, or be otherwise formed in such a manner as to adapt it for reception within the mortar space which underlies the first brick that is rested upon the floor. When the mortar is finally placed in this space, the plate will be securely held against displacement so that a firm anchorage for the strip is provided.

80

85

90

95

It will be understood that the various forms of anchorage herein described will each consist of a plurality of plates that are positioned along the wall or partition at desired intervals so as to effect a secure connection with the strip. Devices of this character may be produced with the aid of dies at small expense, and possess the advantage of being readily installed as the building operation advances. In accordance with common practice the base board is adapted to overlie the rear edge of the strip, and because of this relationship of the parts the strip cannot work loose from its anchorage unless the base board be first removed to permit the necessary movements for this purpose.

100

105

I claim:

1. In combination with a floor from which rises a wall, a carpet strip rested on the floor adjacent the wall, and an anchorage for the strip including means which is embedded therein from its under side and which also engages the wall upon a face remote from the strip, substantially as described.

110

2. In combination with a floor from which rises a wall, a carpet strip adapted to be rested upon the floor adjacent the wall, and an anchorage for the strip also rested upon the floor and connected with the wall, the

120

125

130

anchorage having means which upstands from the floor to bite into the strip when the latter is driven down thereupon, substantially as described.

5 3. In combination with a floor from which rises a wall, a carpet strip adapted to be rested on the floor adjacent each of the opposite sides of the wall, a common anchorage for the two strips adapted to be rested 10 on the floor and extended through the wall to connect at its opposite ends with the two strips, substantially as described.

4. In combination with a floor from which rises a wall, a pair of carpet strips rested 15 on the floor, one adjacent each of the opposite sides of the wall, and a common anchorage for the strips also rested on the floor and extended through the wall to connect with the two strips, the anchorage having 20 means which engages with the vertical faces of the wall to center the anchorage relative thereto, substantially as described.

5. In combination with a floor from which rises a wall, a pair of carpet strips rested 25 on the floor one adjacent each of the opposite sides of the wall, and means extending through the wall in engagement with the two strips adapted to hold the same against the wall, substantially as described.

30 6. In combination with a floor from which rises a wall, a carpet strip rested on the floor adjacent the wall, and an anchorage for the

carpet strip having means which engages a vertical face of the wall and other means including a plurality of teeth with each other adapted to bite into the strip, substantially as described.

7. In combination with a floor from which rises a wall, a carpet strip rested on the floor adjacent the wall, means anchored against movement relative to the wall adapted also to bite into the strip from its under side to prevent movement of the strip from the wall, and a base board attached to the wall in overlying relation to a portion of the strip to thereby hold the same upon the floor, substantially as described.

8. In combination with a floor from which rises a wall a carpet strip rested on the floor adjacent the wall, and an anchorage 50 for the strip having a connection with the wall and means adapted to pierce the strip to be clinched thereupon, substantially as described.

9. In combination with a floor from which rises a wall, a carpet strip rested on the floor adjacent the wall, and an anchorage secured to the floor adapted also to bite into the strip to hold the same relative to the wall, substantially as described.

MAHLON O. KASSON.
